UNITED STATES PATENT OFFICE.

WALTER P. ALBERT, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed April 13, 1921. Serial No. 460,888.

To all whom it may concern:

Be it known that I, WALTER P. ALBERT, a citizen of the United States, residing at East Orange, in the county of Essex, State 5 of New Jersey, have invented certain new and useful Improvements in Telephone-Exchange Systems, of which the following is a full, clear, concise, and exact description.

This invention relates to improvements in 10 automatic telephone exchange systems and more particularly to improvements in telephone exchange systems of large capacity.

More specifically the invention is an improvement on systems of the type shown in 15 a patent to A. E. Lundell and J. J. Wynne, No. 1,501,676, in which a translator switch with its attendant advantages in the way of common cross connections through a common impulse generating device, is utilized.

It is the object of this invention to provide a system in which a translator switch is employed which may be positioned under the control of a calling subscriber, and in 20 which registrations are transferred from such translator switch to secondary registering devices where they are used to control a sending device.

A feature of the invention is the method employed for transferring the registration 25 from the translator switch to the secondary registers.

Other features reside in novel controlling circuits.

It is thought that the invention will best 30 be understood from the following detailed description, reference being had to the accompanying drawings.

Referring to the drawings, Figures 1, 2 35 and 3 when taken in order from left to right, with Fig. 4 beneath Fig. 2, and Fig. 5 at the right of Fig. 4, illustrate a portion of the circuits and apparatus of a telephone office in which the present invention is contained.

In Fig. 1 is shown a calling subscriber's 40 line terminating in an individual line switch adapted to extend the line to an idle trunk circuit.

Fig. 2 illustrates a trunk circuit accessible 45 to the individual line switch and which terminates in a first or district selector switch. This figure also shows a step-by-step sender selector switch for associating the circuits of the district switch with one of a plurality 50 of register sender mechanisms.

Fig. 3 shows a second or office selector switch accessible to the district switch and which serves to extend the calling line over trunks to other switches either in the same or in distant offices.

Fig. 4 illustrates a sender and controlling mechanism arranged to receive series of impulses transmitted over a calling subscriber's line to record the office and numerical designation of a called subscriber's line and to 60 control the automatic switches for the purpose of extending a connection in accordance with the registered designation. This figure also illustrates a class switch, the function of which is to govern the sending mechanism in accordance with the class of the call recorded.

Fig. 5 shows diagrammatically a two movement step-by-step switch arranged to be positioned directly by impulses from the 65 calling subscriber's line to determine the routing of the connection to the proper office. This figure also shows an impulse generating device common to all the senders of the exchange, and a set of register relays for controlling the counting relays of Fig. 4. A plurality of step-by-step registers are also indicated, their function being to record the 70 numerical designation of the desired line in the called office.

The individual line switch of Fig. 1, the sender selector of Fig. 2, the progression switch of Fig. 4, and the step-by-step registers of Fig. 5 are preferably of a mechanical construction, similar to that shown and described in a patent to O. F. Forsberg and R. M. De Vignier No. 1,472,465.

The district and office switches are of the well-known power driven panel type, a complete description being given in the patent 75 to Craft and Reynolds, 1,123,696, issued January 5, 1915.

The sequence switches 210, 310, 410 and 80 440 are the same in structure and principle as the one illustrated in detail in the patent to Reynolds and Baldwin, 1,127,808, issued February 9, 1915. The sequence switches 210 and 310 control respectively the contacts shown in Figs. 2 and 3. In Fig. 4, however, the sender sequence switch 440 governs 85 all contacts shown in the space above and to the right of the broken line, while the class sequence switch 410 controls the remaining contacts.

In the lower part of Fig. 4 a progression 90

switch is provided having five brushes 411, 412, 413, 414 and 415, each cooperating with a circular row of terminals. This switch performs the necessary change over functions for associating the impulse circuit in succession with the translator switch and with the registers shown in Fig. 5.

The translator switch of Fig. 5 comprises an ordinary step-by-step switch having a primary vertical movement and a secondary rotary movement, and is arranged to operate a brush set comprising five brushes mounted on the same shaft.

The first two series of impulses cause the setting of the translator switch, identifying the particular office to which the connection is to be extended. According to the manner in which connections are handled in the called office, as for example, in a full mechanical or semi-mechanical manner, the class sequence switch 410 takes up a setting to govern the operation of the sender in controlling the extension of the particular connection involved. Some of the outlying offices served through the office shown in the drawing will be provided with switches for handling incoming calls on a full mechanical basis. Calls to these offices constitute one class. Again other offices will be equipped with call indicators at an operator's position for completing the connections manually. These offices will constitute another class. Similarly there may be several other classes of calls that will have to be taken care of. For this purpose the class sequence switch 410 is provided and is variably set, as will hereinafter be explained in detail, in accordance with the terminal on which the brush 511 is positioned, under the control of the impulse generating device.

The first two series of impulses sent by the subscriber to position the translator switch determine the district brush, district group, office brush and office group selections to select a trunk, such as trunk 328, 329 leading to the office containing the called line. In other words, the first two letters or numerals identifying the called office determine the vertical and rotary movements of the translator switch for the purpose of selecting this office.

Following the transmission of the first two series of impulses for setting the translator switch, a subscriber sends four series of impulses to identify the digits of the called line party by causing the variable setting of the numerical registers. The banks of each of these registers may be wired in any convenient manner to the counting relays in order to control incoming and final switches or call indicators either in the local office or in a distant office selected by the district and office switches illustrated in Figs. 2 and 3. Inasmuch as the present

invention relates more particularly to the translator switch and the register relays of Fig. 5 and the manner of controlling the same, it has not been considered necessary to illustrate and describe the controlling mechanism in further detail nor to show the different types of apparatus that may be installed in distant called offices.

A detailed description of the operation of the system will now be given. For this purpose it will be assumed that the subscriber of line 100 desires to converse with a subscriber whose line terminates in an office identified by the code No. 37. In practice it is probably more convenient to identify the offices by letter codes which may be taken as abbreviations of the names of the offices. For example, the called office may be known by the code A B and the manipulation of the subscriber's dial 101 to transmit the letters A B would in effect cause the transmission of the digits 3 and 7.

To initiate a call the subscriber removes his receiver from the switchhook whereby a circuit is established from battery through the right-hand winding of line relay 103, back contact and inner lower armature of relay 104, over the loop of the calling substation 100, to ground at the upper armature and back contact of relay 104. Relay 103 becomes energized and completes a circuit from battery through the winding of stepping magnet 105, armature and contact of said magnet, lowermost armature and contact of relay 104, right-hand armature and front contact of relay 103 to ground through the brush 111 and terminal 114. Magnet 105 energizes, interrupts its own circuit, deenergizes, and steps the brushes 106, 107, 108, 109, 110 and 111 forward one step. Brush 109 thereupon engages the segment 113 and battery potential is supplied to the test terminal 102 of the calling line 100 in the multiple banks of all final selector switches having access to this line. In this manner the calling line is rendered busy. The above traced circuit is again completed for magnet 105 by way of brush 11 and terminal 119, and the switch continues to the next set of terminals which represent the first of a plurality of trunk circuits leading to district selector switches. So long as the individual switch encounters the terminals of busy trunks, brush 111 finds a ground potential on the test terminals 120 of such trunks and the switch continues to rotate. When the first idle trunk 115, 116 is reached no ground potential is present on terminal 120 and, consequently, the stepping magnet 105 ceases to advance the switch.

Since the trunk 115, 116 is idle, the sequence switch 210 of the district switch associated with such trunk is standing in 130

position 1. A circuit is then closed from battery through contact of sequence switch spring, 203, back contact and left-hand armature of relay 206, conductor 118, terminal 120, brush 111, contact, left-hand armature and left-hand winding of relay 103, through both windings of relay 104, in series, to ground. Relay 104 becomes energized in this circuit and locks up in 10 a circuit as follows: battery, through the winding of relay 206, left-hand make-before-break contact of relay 205, lower contact of sequence switch spring 245, conductor 117, terminal 121, brush 110, middle 15 lower armature and contact of relay 104, upper winding of said relay to ground. Relay 104, therefore, remains energized, while relay 206 also attracts its armatures. Relay 206, at its left-hand armature and back 20 contact, opens the circuit through the left-hand winding of relay 103, which caused the original energization of relay 104. Relay 103, consequently, becomes deenergized.

Relay 206, on attracting its armatures, 25 completes a circuit from battery through the right-hand winding of relay 212, lower left-hand contact of sequence switch spring 214, contacts of sequence switch spring 208, to ground at the contact and right-hand 30 armature of relay 206. Relay 212 becomes energized and closes a circuit from ground to the winding of sequence switch magnet 210, left-hand contact of sequence switch spring 215, front contact 35 and right-hand armature of relay 212, lower contact of sequence switch spring 213 to ground. Sequence switch 210 advances from position 1 to position 2. A circuit is now closed from ground over the upper 40 left-hand contact of sequence switch spring 209, conductor 118 to multiples of terminal 120 to hold the trunk busy.

Should the test brush 241 of the sender selector switch chance to be standing on 45 the terminals of a busy sender at this time, relay 207 of some other switch is energized, as will be later explained, and a circuit is provided for maintaining the operation of relay 212. This circuit may be traced 50 from battery through the left-hand winding and contact and left-hand armature of relay 212, upper left-hand contact of sequence switch spring 251, lower contact of sequence switch spring 220, conductor 252, brush 241, 55 thence over the multiple of the test terminal individual to the busy sender, to the brush 241 of the sender selector that is rendering said sender busy, to ground at the inner left-hand armature of the operated relay corresponding to the relay 207, shown in the figure. Relay 212 remains energized in position 2 of sequence switch 60 210, and, in so doing, provides a circuit for the stepping magnet 211 for advancing 65 the brushes 239, 240, 241, 242, 243, and 244 of the sender selector switch shown, to search for the terminals of an idle sender. The circuit for magnet 211 may be followed from grounded battery through the contact, armature and winding of said magnet, conductor 253, left-hand contact of sequence switch spring 218, front contact and right-hand armature of relay 212, lower contact of sequence switch spring 213 to ground. At the same time a circuit is maintained 70 from battery through the contact, armature and winding of magnet 211, through the winding of relay 207, to ground at the lower left-hand contact of sequence switch spring 209. Due, however, to the shunt provided by the above traced circuit, sufficient current does not flow through the winding of relay 207 to energize the latter. Stepping magnet 211 interrupts its own circuit and advances the brushes of 75 the sender selector in a step-by-step movement to search for an idle register sender. When the first idle sender is reached, relay 212 becomes deenergized since no ground potential is found on the multiple terminal 80 engaged by the test brush 241. Relay 212 opens the direct circuit to ground for the magnet 211. Magnet 211 is now included in series with relay 207, and this relay 85 attracts its armatures. The magnet 211 does not continue to operate in view of the high resistance of relay 207. Relay 207, at its inner left-hand armature, applies a ground potential to the test terminal to render the 90 selected sender busy to other sender selector switches. Relay 212, on retracting its armatures, completes a circuit as follows for driving the sequence switch 210 out of position 2 and into position 3: battery, through the winding of the power magnet 95 100 of said sequence switch, right-hand contact of sequence switch spring 215, back contact and right-hand armature of relay 212, lower contact of sequence switch spring 213 to ground. Relay 207 also closes a circuit from ground over its inner left-hand armature, brush 241, contacts of spring 403 of the class sequence switch 410, winding of relay 402 to battery and ground. Relay 105 402 locks up over its inner armature and 110 at its outer armature closes a circuit by way of the upper left-hand contact of sequence switch spring 408 for driving sequence switch 410 into position 3.

An idle sender having been selected, and 115 with sequence switch 210 in position 3, an impulse circuit is established from the calling subscriber's line through to the impulse relay 400 of said sender. This circuit may be traced from battery through the winding of impulse relay 400, brush 240, outer left-hand armature and contact of relay 207, lower contact of sequence switch spring 120 201, conductor 116, terminal 122, brush 108, front contact and inner lower armature of 125 130

relay 104, through the loop of substation 100, upper armature and front contact of relay 104, brush 106, terminal 123, conductor 115, left-hand contact of sequence 5 switch spring 200, brush 239, right-hand winding of coil 401, to ground. Relay 400 becomes energized and completes a circuit over its armature and front contact for the slow to release relay 404. Relay 404 closes 10 a circuit from ground through its outer left-hand armature and contact, conductor 425, vertical off normal contact 531, winding of relay 500 to battery and ground. Contact 531 is controlled by the shaft of the translator switch and is closed during the time 15 said shaft is in its normal position. Relay 404 also completes a circuit from ground through the right-hand winding of the tone coil 475, left-hand winding of coil 401, 20 inner left-hand armature and contact of relay 404, conductor 409, terminal 434, brush 414 of the control switch, to ground. Current flowing in this circuit induces a 25 current in the right-hand winding of the coil 401, which is transmitted over the impulse circuit above traced, to produce a characteristic sound in the calling subscriber's receiver. This sound indicates that a sender has been associated with the calling line and that the subscriber may proceed to transmit impulses.

The subscriber thereupon operates the sending dial 101 to transmit the first digit 3 of the code identifying the office in which the 35 called line appears. The first interruption of the impulse circuit causes the deenergization of relay 400, which completes a circuit from ground through its armature and back contact, right-hand armature and front contact of relay 404, winding of the slow to release relay 405, brush 412, terminal 417, conductor 424, inner right-hand armature and front contact of relay 500, conductor 529, winding of the vertical stepping magnet 504 to battery and ground. The retraction of the armature of relay 400 also completes a circuit from battery through the winding of relay 406, brush 413, terminal 433, conductor 422, contact and outer left-hand armature of relay 500, conductor 560, contact and armature of magnet 504, conductor 529, front contact and right-hand armature of relay 500, conductor 424, terminal 417, brush 412, winding of relay 405, 55 front contact and right-hand armature of relay 404 to ground at the back contact and armature of relay 400. Relay 406 becomes energized and completes a circuit from ground through its outer armature and contact, winding of relay 405, brush 412, terminal 417, conductor 424, and thence, as above traced, through the winding of magnet 504 to battery and ground. Relay 406, is, therefore, energized in a circuit which 60 depends upon the armature and contact of

the vertical stepping magnet 504, and as long as it remains energized a circuit for said magnet is maintained independently of the armature and back contact of relay 400. Should the opening period of the line 70 circuit be abnormally short due to an imperfect dial, or for any other reason, the consequent attraction of the armature of relay 400 does not cause the premature opening of the circuit of the stepping magnet 75 504. The magnet 504 remains energized, depending upon the relay 406, until it has had time to advance the brushes of the switch a full step to position them opposite the first levels of terminals. When the full 80 step has been completed the armature and contact of relay 504 are opened and the circuit of relay 406 is interrupted. Relay 406 thereupon releases its armatures and opens the circuit of the magnet 504, which in turn 85 becomes deenergized. Relay 406, furthermore, maintains a circuit at its inner armature and contact for the slow to release relay 404. Relay 404 is designed to remain 90 operated during the normal periods in 95 which its circuit is opened by the armature of relay 400. If, however, relay 400 remains deenergized for an exceedingly long period, relay 404 cannot become deenergized due to the fact that relay 406 provides a substitute holding circuit therefor.

As the translator switch takes its first step, the contact 531 is opened to interrupt the original energizing circuit of relay 500. Relay 500, however, remains energized in 100 a circuit as follows: from grounded battery, through the winding and front contact and inner left-hand armature of relay 500, conductor 423, contact and armature of the slow to release relay 405, to ground. Relay 405, being of the slow-to-release character, does not retract its armature during the brief interruptions of its circuit at the armature and back contact of the stepping relay 400. On each of the following interruptions 105 of the line circuit in the transmission of the first digit, the brushes 511, 512, 513, 514, and 515 of the translator switch are advanced one step until they are finally positioned opposite the third level of terminals 110 in their respective banks. Following the third impulse, the stepping relay 400 remains energized for a comparatively long period, during which interval the slow-to-release relay 405 is permitted to release its armature. Relay 405 opens the holding circuit 115 of relay 500, which becomes deenergized.

The calling subscriber next operates the sending dial 101 to transmit a series of seven impulses representing the second 125 digit of the office code. On the first opening of the impulse circuit, relay 400 becomes deenergized and completes a circuit from ground through its armature and back contact, right-hand armature and front con- 130

tact of relay 404, winding of relay 405, brush 412, terminal 417, conductor 424, inner right-hand armature and back contact of relay 500, conductor 561, winding of the 5 rotary stepping magnet 503 to battery and ground. A circuit is also closed for the energization of relay 406 as follows: battery, through the winding of said relay, brush 413, terminal 433, conductor 422, left- 10 hand normal contact of relay 500, conductor 562, contact and armature of stepping magnet 503, conductor 561, and thence to ground, as above traced, at the back contact and armature of relay 400. Relay 406, in a 15 manner similar to that previously described, closes a circuit for the rotary stepping magnet 503 to insure that said magnet takes a full step before its circuit is opened. For each of the seven impulses of the second 20 digit the brushes of the translator switch are advanced one step over the third levels of terminals and are finally brought to rest in engagement with the seventh set of terminals in such level. The slow-to-release relay 25 405, which also becomes energized during the transmission of the second series of impulses, completes a circuit from ground through its armature and contact, conductor 423, inner left-hand armature and back con- 30 tact of relay 500, conductor 427, winding of the stepping magnet 416 to battery and ground. Magnet 416 energizes preparatory to advancing the brushes of the control switch when its circuit is opened. After 35 the last impulse has been transmitted, relay 400 remains energized for a period of time sufficient to permit the release of the slow relay 405. Relay 405 opens the circuit of stepping magnet 416, which in turn deenergizes and advances the brushes 411, 412, 413, 414 and 415 to their second position terminals. 40

The two movement step-by-step selective switch has thus been positioned in accordance with the office code to determine the 45 operation of the district and office switches to route the call in the proper direction. The calling subscriber continues to manipulate his dial to transmit the digits corresponding to the numerical designation of 50 the wanted line. In a ten thousand line office the subscriber's line numbers consist of four digits and consequently four numerical registers 540, 545, 550 and 555 55 are provided to take a record of these numbers. When the dial 101 is operated to transmit the first digit of the wanted number, relay 400 becomes deenergized and completes a circuit from ground through its 60 armature and back contact, right-hand armature and front contact of relay 404, winding of relay 405, brush 412, terminal 418, conductor 429, winding of stepping magnet 541 to battery and ground. Magnet 541 energizes and upon its circuit being broken at

the end of the first impulse advances the brushes 542, 543, etc. to the first position terminals. In a similar manner, for each succeeding impulse in the series, the brushes of register 540 are advanced step-by-step 70 until a position corresponding to the first digit is reached. Relay 405 completes the circuit above traced for the stepping magnet 416, and at the end of the series this relay releases to permit the deenergization 75 of said magnet. The brushes 411, 412, 413, etc., of the control switch are advanced to their third position terminals.

The first deenergization of relay 400 in response to the transmission of the second 80 series of impulses of the wanted line number causes a circuit to be closed from ground through the armature and front contact of relay 404, winding of relay 405, brush 412, terminal 419, conductor 430, winding of 85 stepping magnet 546 of the next register, to battery and ground. The register 545 is thereupon moved forward step-by-step in response to the second series of impulses. Relay 405 closes the above traced circuit for 90 the stepping magnet 416, and at the end of the series opens this circuit to permit the control switch to advance to the fourth position.

In a similar manner the next and the last 95 series of impulses are directed to the stepping magnets 551 and 556 of the registers 550 and 555 respectively, and these registers take up their corresponding positions. Following the transmission of the last series 100 of impulses the control switch is advanced to its sixth position.

The circuits of this system are arranged to start the district and office selections immediately following the setting of the translator switch, or, in other words, as soon as the record of the called office has been received. While the district and office switches are being positioned the subscriber may continue the dialing operation to register the 110 number of the called line.

Immediately after the translator switch has been positioned, the control switch is moved to its second position terminals as explained. A circuit is then completed from 115 grounded battery through the winding of relay 407, terminal 435, brush 414 to ground. Relay 407 becomes energized and locks up in the circuit extending through its left-hand armature and front contact to ground 120 by way of a contact of sequence switch spring 499. Relay 407 completes circuits at its right-hand armatures for simultaneously recording on the register relays of Fig. 5 the registration which controls the selection of a brush set at the district selector.

It might be well to observe at this point that relays 601, 602, 603, and 604 are used to set up a registration in accordance with which class sequence switch 410 will be 130

- positioned. As previously explained the setting of sequence switch 410 will control the routing of the call. Relays 613, 614, 615, 616, 617 and 618 are used to control brush selection both at the district switch and at the office switch. Relays 606, 607, 608, 609, 610, and 611 are used to control group selection both at the district switch and at the office switch.
- 10 The class controlling relays 601, etc., and the district brush control relays 613, etc., are positioned simultaneously under the control of impulser 623 in accordance with the position assumed by the translator brush set.
- 15 The class sequence switch then hunts a position determined by which one of the class control register relays has been actuated. The sender sequence switch is then advanced and district brush selection takes place
- 20 under control of the counting relays in accordance with which one of the chain of relays 613, etc. has been actuated. After brush selection at the district switch the sender sequence switch is advanced and
- 25 allows the district brush controlling relays to be released. The district group controlling relays 606, etc., are then brought under the control of the impulser 623 and a registration accomplished to control the
- 30 selection of a desired group in the district. After the district switch has completed group selection the district group controlling relays are released and relays 613, etc., are again brought under the control of
- 35 the impulser to control brush selection at the office switch. The completion of brush selection at the office brings about the release of relays 613, etc., and causes relays 606 etc., to be associated with the impulser to cause a registration in accordance with
- 40 which office group selection may be accomplished.

Returning now to the detailed description of operation, the energization of relay 407 completes a circuit from grounded battery, winding of relay 621, Fig. 5, right-hand armature and back contact of relay 600, conductor 624, contacts of sequence switch spring 498, outer right-hand armature and front contact of relay 407, conductor 625, translator brush 511 and its associated contact, brush 626, a conducting portion of the constantly rotating drum of the impulser and thence to ground as soon as the impulser brush 626 is brought into an engagement with the conducting portion accessible to it. It should be observed at this time that the impulser 623 comprises a constantly rotating drum driven by any suitable source of power and comprising a number of conducting and insulating segments served by a plurality of brushes. In order to more clearly show the relation between the various segments on the drum it has been developed into a plane surface. As shown in the

drawing, conducting portions of the drum are indicated in black.

Relay 621 is energized in the above traced circuit and prepares, by way of its armatures, circuits for relays 601, 602, 603 and 604. Of these relays only relay 603 will be energized due to the fact that while brush 626 is in engagement with a conducting segment, brush 627 is the only other brush to engage a conducting segment. The circuit of relay 603 extends from grounded battery, left-hand winding of relay 603, conductor 628, armature 629 and its front contact, conductor 630, brush 627 and the conducting segment engaged by it, to ground. Relay 603 is energized in this circuit and completes a locking circuit for itself from grounded battery, right-hand winding of relay 603, right-hand armature and front contact of relay 603, winding of relay 600, conductor 631, outer right-hand armature and back contact of relay 471 to ground. Relay 600 is energized in this circuit and completes a circuit from grounded battery, power magnet of class sequence switch 410 (Fig. 4) lower right-hand contact of sequence switch spring 408, inner right-hand armature and back contact of relay 471, conductor 632, left-hand armature and front contact of relay 600 to ground. Class sequence switch 410 is put into motion and continues in motion until relay 471 is energized. The control of the energizing circuit of relay 471 is successively shifted to the various class control relays by way of the contacts of sequence springs 472 and 473. When sequence switch 410 reaches position $7\frac{3}{4}$ a circuit is completed from grounded battery, winding of relay 471, lower right-hand contact of sequence switch spring 472, upper right-hand contact of sequence switch contact 473, conductor 633, left-hand armature and front contact of relay 603 to ground. Relay 471 is energized in this circuit and locks up through its left-hand armature and front contact to ground by way of the contact of sequence switch spring 497. The energization of relay 471 opens at its inner right-hand armature the driving circuit of sequence switch 410 and causes the sequence switch to come to rest in position 8, which it will be assumed is the position in which a full mechanical call is to be set up. The energization of relay 471 also opens at its outer right-hand armature the locking circuit for relays 603 and 600 and these relays deenergize. It should be observed that when relay 600 was energized the circuit for relay 621 was opened and this relay deenergized. This however, is without effect since relay 603 remains locked up as previously described.

As soon after the energization of relay 407, as brush 634 engages a conducting segment of the impulse drum, a circuit is com-

pleted from ground, brush 634 and its associated segment, conductor 635, inner right-hand armature and front contact of relay 407, lower contact of sender sequence spring 496, conductor 495, right-hand armature and back contact of relay 612, winding of relay 619 to grounded battery. Relay 619 is energized and prepares through its armatures circuits for relays 613 to 618 inclusive. 10 During the time that brush 634 is engaging a conducting segment of the drum, brush 636 is the only other brush to be engaging a conducting segment. Relay 613 is therefore, the only relay to be energized at this time. 15 The circuit of relay 613 extends from grounded battery, left-hand winding of relay 613, armature 637 and its front contact, brush 636 and the associated conducting segment of the impulse drum to ground. 20 Relay 613 is energized in this circuit and completes a locking circuit for itself from grounded battery, right-hand winding of relay 613, right-hand armature and front contact of relay 613, winding of relay 612, conductor 638, upper contact of sequence switch spring 494 to ground. The energization of relay 612 opens at its right-hand armature the circuit of relay 619 and this relay deenergizes. At its left-hand 25 armature relay 612 completes a circuit from grounded battery, power magnet of sender sequence switch 440, lower contact of sequence switch spring 439, conductor 493, left-hand armature and front contact of relay 612 to ground, for moving this sequence switch out of position 1 and into position 2. 30 As soon as sequence switch 440 reaches position 2 a circuit is completed from grounded battery, left-hand winding of line relay 212 (Fig. 2), upper right-hand and lower left-hand contacts of sequence switch spring 251, right-hand armature and front contact of relay 207, brush 242 and its associated terminal, contact of sequence switch 445, contact of sequence switch spring 443, winding of stepping relay 445, armature and back contact of relay 466 and the contact of sequence switch spring 444 to ground. Relay 212 is energized in this circuit and locks up through its left-hand armature and front contact to the above traced circuit by way of the left-hand contacts of sequence switch 251. The energization of relay 212 also completes a circuit from grounded battery, power magnet of sequence switch 210, upper left-hand contact of sequence switch spring 215, right-hand armature and front contact of relay 212 and lower contact of sequence switch 213 to ground, for moving this sequence switch out of position 3 and into position 4. 55

In position 4 of sequence switch 210 a circuit is completed from grounded battery, winding of up-drive magnet 224, right-hand contact of sequence switch spring 218, right-

hand armature and front contact of relay 212, lower contact of sequence switch spring 213 to ground. The energization of magnet 224 causes the brush shaft 248 to be moved upward in a brush selecting movement. 70

It should be observed that stepping relay 445 was energized in series with the line relay 212. The energization of relay 445 completes a circuit from ground, armature and contact of relay 445, upper contact of sequence switch spring 464, conductor 465, left-hand armature and front contact of relay 613, conductor 639, (Fig. 5 and in Fig. 4 that part of conductor 639 connected to the contact of relay 492) left-hand armature 80 and back contact of relay 492, the winding of the No. 0 counting relay, and contact of sequence switch spring 491 to grounded battery. The No. 0 counting relay is energized in this circuit. As the brush shaft 248 approaches the first brush tripping position commutator brush 228 engages a conducting portion of commutator 230 and completes a holding circuit for relay 212 extending from grounded battery, winding of relay 212, upper left-hand contact of sequence switch spring 251, upper right-hand contact of sequence switch spring 220, a conducting portion of commutator 230, commutator brush 228, and the contact of sequence switch spring 223 to ground. Stepping relay 445 is deenergized in this circuit and allows the No. 0' counting relay and relay 466 to be energized in the well known manner. The energization of the 0' relay completes 100 a circuit from grounded battery, power magnet of sequence switch 440, upper left-hand contact of sequence switch spring 439, left-hand armature and front contact of the No. 0' counting relay to ground, for moving 105 this sequence switch out of position 2 and into position 3. The energization of relay 466 opened the lower branch of the holding circuit of relay 212 and when a moment later commutator brush 228 engages an insulating segment of commutator 230, relay 212 is deenergized, opening at its right-hand armature the circuit of up-drive magnet 224 and bringing the brush shaft to rest in a position wherein the first set of brushes may 110 be tripped. The deenergization of relay 212 also completes a circuit from grounded battery, power magnet of sequence switch 210, upper right-hand contact of sequence switch spring 215, right-hand armature and 120 back contact of relay 212, and the lower contact of sequence switch spring 213 to ground, for moving this sequence switch out of position 4 and into position 5.

Referring now to the sender circuits it 125 should be noted that when sender sequence switch 440 left position 2 the locking circuit for the counting relays is opened at sequence switch springs 490 and 491 and these relays are deenergized. At the same time the lock- 130

ing circuit of relay 613 and relay 612 is opened at sequence switch spring 494, and these relays deenergize.

With the sequence switch 440 in position 3 circuits are completed for setting the group controlling register relays of Fig. 5, as soon as brush 640 engages a conducting segment of the impulser drum. When this occurs a circuit is completed from grounded battery, 10 winding of relay 620, right-hand armature and back contact of relay 605, conductor 641, upper contact of sequence switch spring 489, conductor 642, translator brush 513 and its associated contact, brush 640 and a conducting segment of the impulser to ground. Relay 620 is energized in this circuit and prepares circuits for relays 606 to 611 inclusive. Since brush 643 is the only other brush which engages a conducting segment of the 15 impulse drum while brush 640 is effective, only relay 609 can be energized. The circuit of relay 609 extends from grounded battery, left-hand winding of relay 609, armature 644, and the front contact of relay 620 associated with it, brush 643 and its associated conducting segment to ground. Relay 609 is energized in this circuit and locks up through its right-hand winding and right-hand armature and front contact 20 through the winding of relay 605, conductor 645, to ground, at the lower contact of sequence switch spring 494. Relay 605 is energized in this circuit and at its right-hand armature opens the circuit of relay 620, which thereupon releases. Relay 605 at its left-hand armature completes a circuit from ground to conductor 488, upper right-hand contact of sequence switch spring 439, winding of the power magnet of sequence 25 switch 440 to grounded battery. Sequence switch 440 is caused to move out of position 3 and into position 4 upon the completion of this circuit.

With sequence switch 440 in position 4 and the district sequence switch in position 45 5 the fundamental circuit is again completed as above traced to control group selection at the district switch. This circuit corresponds to the one hereinbefore traced 50 with the exception that the contacts of sequence switches 210 and 440 are closed in different positions. Relay 212 upon energizing in the fundamental circuit closes a circuit for driving switch 210 out of position 5 and into position 6. This circuit leads from battery through the winding of the magnet 210, left-hand contact of sequence switch spring 215, front contact and right-hand armature of relay 212, and the 55 lower contact of sequence switch spring 213 to ground. Relay 212 remains energized in position 6 of sequence switch 210, in a locking circuit extending from grounded battery through its left-hand winding and contact, and left-hand armature, and the upper

left-hand contact of sequence switch spring 251 to ground over the fundamental circuit as described. Relay 212 again closes the circuit for the up-drive magnet 224 over the right-hand contact of sequence switch spring 218. Brush shaft 248 is advanced and brushes 233, 234, and 235 are tripped into engagement with the terminals of the bank due to the fact that trip magnet 225 was energized in positions 5 to 6 of sequence 70 switch 210 by way of a circuit extending from grounded battery, winding of magnet 225, contact of sequence switch spring 221 to ground.

The stepping relay 445, which again energized in the fundamental circuit completes a circuit from ground through its armature and contact, lower contact of sequence switch spring 464, conductor 487, left-hand armature and front contact of relay 609, conductor 646, (Figs. 5 and 4), armature and back contact of the No. 3' counting relay, and the winding of the No. 3 counting relay to grounded battery by way of sequence switch spring 491. The No. 3 counting relay becomes energized and completes a series holding circuit for itself and the No. 3' counting relay. As the brush shaft 248 approaches the first group of terminals, commutator brush 227 engages the first conducting segment of commutator 231 and a circuit is closed from battery through the left-hand winding and contact and left-hand armature of relay 212, upper left-hand and lower right-hand contacts of sequence switch spring 251, conducting segment of commutator 231, brush 227, contact of sequence switch spring 223 to ground. Relay 212 remains energized and the stepping relay is shunted down. Relay 445 deenergizes and permits the energization of the No. 3' counting relay in series with the No. 3 counting relay. As soon as commutator brush 227 engages an insulating segment of commutator 231, stepping relay 445 is again energized and causes the energization of the No. 2 counting relay. The counting relays are successively operated, until the No. 0 and No. 0' counting relays are energized, and the fundamental circuit is opened. The 100 No. 0' counting relay closes a circuit including a contact of sequence switch spring 439 for advancing the sender sequence switch out of position 4 and into position 5. As sequence switch 440 leaves position 4 the 105 contacts of sequence switch springs 490 and 491 are opened, and the counting relays are all restored. In position 5 of sequence switch 440 the holding circuit of relays 609 and 605 is opened at the lower contact of sequence switch spring 494 and these relays 110 are released.

As soon, following the opening of the fundamental circuit at the armature and contact of relay 466, as brush 227 encoun- 115

ters an insulating segment of the commutator 231, relay 212 becomes deenergized and opens the circuit of the updrive power magnet 224. Relay 212 also closes a circuit 5 from battery through the winding of sequence switch magnet 210, right-hand contact of sequence switch spring 215, back contact and right-hand armature of relay 212, lower contact of sequence switch spring 213 to ground. Sequence switch 210 thereby advances from position 6 into position 7. With the district sequence switch 210 in position 7, a circuit is immediately closed 10 from grounded battery through the right-hand winding of relay 212, lower left-hand contact of sequence switch spring 214, upper contact of sequence switch spring 208, contact and right-hand armature of relay 206 to ground. Relay 212 becomes energized 15 and completes a circuit from battery through the winding of sequence switch magnet 210, left-hand contact of sequence switch spring 215, front contact and right-hand armature of relay 212, upper contact of sequence switch spring 213, right-hand armature and contact of relay 205 to ground. It 20 will be noted that relay 205 was energized in position 2 of sequence switch 210 in a circuit including the upper right-hand contact of sequence switch spring 209. The sequence switch 210 advances out of position 7 and into position 8. Relay 212 remains operated provided the trunk in the group upon the terminals of which the 25 brushes 233, 234 and 235 are standing is busy. In this case the test brush 235 is standing on a grounded test terminal and the following locking circuit is closed for relay 212: grounded battery, through the 30 left-hand winding and contact and left-hand armature of relay 212, upper contacts of sequence switch spring 222, brush 235, and thence to the grounded test terminal of the busy trunk. It will be noted that the 35 upper left-hand contact of sequence switch spring 222 does not close until in position 7½. This closure, however, takes place prior to the opening of the original energizing circuit of relay 212, as the lower left-hand contact of sequence switch spring 214 opens when sequence switch 210 moves out of position 7½. Relay 212 remaining energized, a circuit is completed for the updrive power magnet 224, from grounded battery 40 through the winding of said magnet, right-hand contact of sequence switch spring 218, front contact and right-hand armature of relay 212, lower contact of sequence switch spring 213 to ground. The brush shaft 248 is driven upwardly and brushes 233, 234 and 235 pass over the bank terminals to 45 search for an idle trunk. When the first idle trunk is encountered, no ground potential being found on the test terminal 238 thereof, relay 212 becomes deenergized and

opens the circuit of the updrive power magnet 224. Relay 212 also closes a circuit as follows for driving sequence switch 210 out of position 8 and into position 10: grounded battery, through the winding of the magnet 50 of said sequence switch, right-hand contact of sequence switch spring 215, back contact and right-hand armature of relay 212, lower contact of sequence switch spring 213 to ground. 75

With sequence switch 440 in position 5 circuits are completed for positioning the brush selection controlling relays of Figure 5. As soon as brush 647 engages a conducting segment of the impulser drum, a 80 circuit is completed from grounded battery, winding of relay 619, right-hand armature and back contact of relay 612, conductor 495, upper right-hand contact of sequence switch spring 496, conductor 648, translator brush 514 and its associated terminal, impulser brush 647, and a conducting segment of the impulser drum to ground. Relay 619 is energized in this circuit and prepares circuits 85 for relays 613 to 618 inclusive. Since brush 649 is the only other brush which engages a conducting segment of the impulser drum while brush 647 is effective, only relay 614 can be energized. The circuit of relay 614 90 extends from grounded battery, left-hand winding of relay 614, armature and front contact of relay 619, brush 649 and its associated conducting segment to ground. Relay 614 is energized in this circuit and locks up 95 through its right-hand winding and right-hand armature and front contact through the winding of relay 612, conductor 638, and the upper right-hand contact of sequence switch spring 494 to ground. Relay 612 is energized in this circuit and at its 100 right-hand armature opens the circuit of relay 619, which thereupon releases. Relay 612 at its left-hand armature completes a circuit from ground to conductor 493, lower left-hand contact of sequence switch spring 439 and the winding of the power magnet of sequence switch 440 to grounded battery. Sequence switch 440 is caused to move out of position 5 and into position 6 upon the completion of this circuit. 105

With sequence switch 440 in position 6 and the district sequence switch in position 10, conditions have been established for controlling the setting of the office selector switch shown in Figure 3. The fundamental circuit is again established at this time and extends from grounded battery through the right-hand winding of relay 300, lower left-hand contact of sequence switch spring 306, left-hand contact of sequence switch spring 305, conductor 239, terminal 236, brush 233, right-hand contacts of sequence switch spring 246, conductor 254, right-hand armature and front contact of relay 207, brush 242 and its 110 associated terminal. 115

ciated contact, contact of sequence switch spring 447, contact of sequence switch spring 448, winding of stepping relay 445, armature and back contact of relay 466, contact of sequence switch spring 446, brush 243 and its associated contact, conductor 255, right-hand contacts of sequence switch spring 247, brush 234, terminal 237, conductor 240, contact of sequence switch spring 10 304 to ground. Relay 300 becomes energized and closes a circuit from ground through its left-hand armature and front contact, lower left-hand contact of sequence switch spring 303, winding of sequence switch magnet 310 to battery and ground. Sequence switch 310 advances out of position 1 and into position 2. Relay 300 remains energized in a locking circuit from battery through its right-hand winding, its 15 outer right-hand armature and front contact, lower right-hand contact of sequence switch spring 306, left-hand contact of sequence switch spring 305 and thence to ground as traced over the fundamental circuit. Relay 300 completes a circuit for the 20 up-drive magnet 317 from grounded battery through the winding of said magnet, lower right-hand and upper left-hand contacts of sequence switch spring 302, left-hand armature and front contact of relay 300 to ground. The brush shaft 326 is thereby advanced under the control of magnet 317.

Stepping relay 445 is energized in the 35 fundamental circuit, and completes a circuit from ground through its armature and contact, upper contact of sequence switch spring 464, conductor 465, left-hand armature and front contact of relay 614, conductor 650, (Figs. 5 and 4) armature and back contact of the No. 1' counting relay, winding of the No. 1 counting relay to grounded battery, by way of the contact of sequence switch spring 491. The No. 1 counting relay is energized and prepares a locking circuit for itself and the No. 1' counting relay. Each time a conducting segment of the commutator 314 is encountered by commutator brush 312, a circuit is completed 40 from grounded battery through the right hand winding of relay 300, its right-hand armatures and front contacts, right-hand contacts of sequence switch spring 306, conducting segment of commutator 314, brush 312 to ground. Relay 300 remains energized 45 in this circuit and stepping relay 445 is shunted down. Consequently the counting relays are successively energized and locked up in the well-known manner until finally 50 the zero counting relays are operated. The fundamental circuit is then opened at the armature and contact of relay 466, and a circuit is completed from ground through the armature and contact of the No. 0' 55 counting relay, the upper left-hand contact

of sequence switch spring 439, through the winding of sequence switch magnet 440 to battery and ground. Sequence switch 440 is advanced out of position 6 and into position 7 whereupon the actuated counting relays are deenergized, and the holding circuit of relays 612 and 614 is opened at the upper right-hand contact of sequence switch spring 494.

As soon after the opening of the fundamental circuit at the sender, as brush 312 engages an insulating segment on commutator 314, relay 300 releases its armatures and opens the circuit of the up-drive magnet 317. Relay 300 also completes a circuit from ground through its left-hand armature and back contact, lower right-hand contact of sequence switch spring 303, winding of sequence switch magnet 310 to battery and ground, for moving this sequence switch out 55 of position 2 and into position 3. The brush tripping magnet 318 is now energized in a circuit closed over the lower contact of sequence switch spring 309. Magnet 318 rotates the trip spindle in order to cause 60 the selected set of brushes to be tripped on the next upward movement of the brush shaft.

With sequence switch 440 in position 7, 65 circuits are completed for positioning the group selection controlling relays of Fig. 5, as soon as brush 652 engages a conducting segment of the impulser drum. When this occurs a circuit is completed from grounded battery, winding of relay 620, right-hand armature and back contact of relay 605, conductor 641, lower contact of sequence switch spring 489, conductor 651, translator brush 515 and its associated contact, brush 652 and the conducting segment of the impulser to ground. Relay 620 is energized 70 in this circuit and prepares circuits for relays 606 to 611 inclusive. Since impulser brushes 627 and 653 both engage conducting segments of the drum during the time that brush 652 is effective, relays 611 and 608 will be energized. The circuit of relay 608 extends from grounded battery, left-hand winding of relay 608, armature and front contact of relay 620, brush 627 and its associated conducting segment to ground. The circuit of relay 611 extends from grounded battery, left-hand winding of relay 611, armature and front contact of relay 620, brush 653 and its associated conducting segment to ground. Relays 608 and 611 are energized in this circuit and lock up 75 through their right-hand windings and right-hand front contacts and armatures to conductor 654 in parallel, and thence through the winding of relay 605, conductor 645, and the lower right-hand contact of sequence switch spring 494 to ground. Relay 605 is energized in this circuit and at its right-hand armature opens the circuit 80

of relay 620, which thereupon releases. Relay 605 at its left-hand armature completes a circuit from ground to conductor 488, upper right-hand contact of sequence switch 439, winding of the power magnet of sequence switch 440 to ground. Sequence switch 440 is caused to move out of position 7 and into position 8.

With office sequence switch 310 in position 3 and the sender sequence switch in position 8 the fundamental circuit is again closed to control the group selecting movement of the office switch. The fundamental circuit may be traced over the path hereinbefore described. Relay 300 becomes energized and closes a circuit from ground through its left-hand armature and front contact, lower left-hand contact of sequence switch spring 303, winding of the power magnet of sequence switch 310 to grounded battery, for moving this sequence switch out of position 3 and into position 4. In this position relay 300 remains energized in a locking circuit from battery through its right-hand winding, right-hand armatures and front contacts, and the lower right-hand contact of sequence switch spring 306 to ground, as previously described. Relay 300 prepares the operating circuit of the up-drive magnet 317, which includes the lower right-hand and upper left-hand contacts of sequence switch spring 302. The brush 326 is now driven upwardly in a group selecting movement.

Referring now to the sender it should be noted that the energization of relay 611 in the group controlling registering relays causes the energization of translator relay 492. The circuit of relay 492 extends from grounded battery through the winding of said relay and thence to ground at the left-hand armature and front contact of relay 611. When stepping relay 445 is energized in the fundamental circuit, a circuit is completed from ground through the armature and contact of the stepping relay, lower contact of sequence switch spring 464, conductor 487, left-hand armature and front contact of relay 608, conductor 655, (Figs. 5 and 4) armature and back contact of No. 2' counting relay, winding of the No. 2 counting relay, and the contact of sequence switch spring 491 to grounded battery. The No. 2 counting relay is energized in this circuit and prepares in the well-known manner, a circuit for the No. 2' counting relay. As soon as brushes 320, 321 and 322 approach the first group of terminals commutator brush 311 engages a metallic segment of commutator 315, and a circuit is closed from battery through the right-hand winding and right-hand armatures and front contacts of relay 300, lower right-hand and upper left-hand contacts of sequence switch spring 306, conducting seg-

ment of commutator 315, brush 311 to ground. The closure of this circuit shunts down the stepping relay and permits the energization of the No. 2' counting relay. As brush shaft 326 is advanced, the counting relays are successively energized due to the action of commutator brush 311 on commutator 315. It should be noted that in the present instance, with the translation relay 492 energized, the Nos. 0 and 0' counting relays are not energized after the No. 1' counting relay has been actuated. The energization of the No. 1' counting relay extends the ground supplied by stepping relay 445 to conductor 639 and thence to the right-hand armature and front contact of relay 492, the right-hand armature and back contact of the No. 9' counting relay and the winding of the No. 9 counting relay to ground. The successive actuation of the counting relays continues until the No. 5' counting relay is energized. The next energization of stepping relay 445 extends ground by way of the right-hand armature and front contact of the No. 5' relay, the left-hand armature and front contact of relay 492, winding of counting relay No. 0, and the contact of sequence switch spring 491 to grounded battery. The No. 0 counting relay is energized in this circuit and upon the subsequent de-energization of stepping relay 445 allows the No. 0' counting relay and relay 466 in parallel therewith to be energized. The energization of relay 466 opens the lower branch of the fundamental circuit while the energization of the No. 0' counting relay completes a circuit including the contact of sequence switch spring 439 for driving sequence switch 440 out of position 8.

Shortly after the fundamental circuit is opened at the sender, commutator brush 311 engages an insulating segment of the commutator 315 and relay 300 is deenergized. Relay 300 opens the circuit of the up-drive magnet 317 and brings the brush shaft with the selected set of brushes into operative relation with the eighth group of outgoing trunks. The deenergization of relay 300 also completes a circuit from grounded battery, winding of the power magnet sequence switch 310, lower right-hand contact of sequence switch spring 303, left-hand armature and back contact of relay 300 to ground for moving this sequence switch out of position 4 and into position 5.

With sequence switch 310 in position 5, a circuit is closed from grounded battery through the left-hand winding of relay 300, upper contacts of sequence switch spring 301 to ground. Relay 300 is energized and closes a circuit from ground through its left-hand armature and front contact, lower left-hand contact of sequence switch spring 303, winding of the power magnet of se-

quence switch 310 to battery and ground for advancing sequence switch 310 out of position 5 and into position 6. Relay 300 remains energized in this position, provided that the first trunk in the selected group upon the terminals of which the brushes 320, 321 and 322 are now standing is engaged. The holding circuit for relay 300 extends from battery through the right-hand winding, right-hand armatures and front contacts of said relay, right-hand contacts of sequence switch spring 308, test brush 322 to the grounded test terminal 325. Relay 300 by remaining energized in position 6 of sequence switch 310, completes a circuit for the up-drive magnet 317 by way of the lower right-hand and upper left-hand contacts of sequence switch spring 302. When the first set of idle terminals is encountered the circuit through the right-hand winding of relay 300 is opened, due to the fact that no ground potential is found on the terminal 325. Relay 300 is however held energized a moment longer due to the existence of a circuit from grounded battery, left-hand winding of relay 300, upper left-hand and lower right-hand contacts of sequence switch spring 301, a conducting segment of centering commutator 316, commutator brush 312 to ground. When, a moment later, brush 312 engages an insulating segment of commutator 316, at which time the selected brush set will be accurately centered on the terminals of the selected trunk, this circuit is opened and relay 300 deenergizes, and opens the circuit of the up-drive magnet and brings the brush shaft to rest. The deenergization of relay 300 also completes the circuit from grounded battery, power magnet of sequence switch 310, lower right-hand contact of sequence switch spring 308, left-hand armature and back contact of relay 300 to ground for moving this sequence switch out of position 6 and into position 7.

In position 7 relay 300 is again energized by means of a circuit extending from grounded battery, left-hand winding of relay 300, upper contacts of sequence switch spring 301 to ground. Relay 300 now closes a circuit through the lower left-hand contact of sequence switch spring 303 to advance sequence switch 310 out of position 7 and into position 8. Relay 300 remains energized in position 8 of sequence switch 310 by means of a circuit from grounded battery through the right-hand winding and right-hand armatures and front contacts of relay 300, the lower contacts of sequence switch spring 308, conductor 327, terminal 238, brush 235, right-hand contacts of sequence switch spring 222 to ground.

After the office selector has been positioned to select trunk 328, 329, the sender sequence switch 440 advances to the posi-

tions assigned for controlling succeeding switches or other mechanism in accordance with the numerical portion of the designation as is clearly explained in Patent No. 1,395,977, November 1, 1921, to F. A. Stearn and F. J. Scudder. It should be noted that the locking circuit of relays 608 and 611 and the holding circuit of relay 605 are opened at the lower right-hand contact of sequence switch spring 494 as soon as sequence switch 440 leaves position 8. These relays therefore deenergize. The register relays of Fig. 5 are now in their normal condition.

When the complete connection has been established the sender sequence switch 440 reaches some position such as 14 and a circuit is closed from ground through the contact 448, brush 244 and its associated contact, upper left-hand contact of sequence switch spring 214, and the right-hand winding of relay 212 to grounded battery. Relay 212 is energized and completes a circuit from grounded battery, winding of the power magnet of sequence switch 210, left-hand contact of sequence switch spring 215, right-hand armature and front contact of relay 212, lower contact of sequence switch 213 to ground, for advancing this sequence switch 210 out of position 10 and into position 15. As the sequence switch 210 leaves position 11 the upper right-hand contact of sequence switch 209 is opened and the circuit of relay 205 is interrupted. Relay 205 remains energized by means of a substitute circuit closed from battery through its winding, contact and armature of relay 204, right-hand armature and front contact of relay 205 to ground. Relay 204, it will be noted, becomes energized in series with the calling subscriber's line over a circuit closed by contacts 200 and 201 as the sequence switch 210 reaches position 10 $\frac{3}{4}$. This circuit includes the battery and the left-hand winding of repeating coil 202.

When the district sequence switch 210 leaves position 11 relay 207 is deenergized and removes the busy condition from the multiple terminals of other sender selector brushes to permit this sender to be taken for use in extending subsequent connections.

At the time the sender sequence switch 440 reaches position 14 a condition is created for causing the release of the translator switch and the numerical registers. To release the translator switch a circuit is completed from grounded battery, through the winding of release magnet 502, off-normal contact 532 and the contact of sequence switch spring 438 to ground. The contact 532 is closed as long as the brush shaft of the translator switch is away from its normal position. Relay 502 becomes energized and causes the release of the switch in the well-known manner. At the same time a

circuit is completed for restoring the progression switch to its normal position. This circuit may be traced from battery through the winding of the stepping magnet 416, 5 armature and back contact of said magnet, conductor 477, brush 411, which it will be recalled, is in engagement with its fifth off-normal contact, and thence to ground by way of sequence switch spring 438. Magnet 416 10 interrupts its own circuit and advances the brushes of the control switch until they reach their tenth position terminals, at which time brush 411 opens the stepping circuit of said magnet. In position 10 of the 15 control switch a circuit is established from ground through the brush 414, terminal 478, conductor 479, thence through the brushes 542, 547, 552 and 557 and the respective off-normal contacts engaged by them, and 20 thence to the back contacts and armatures and windings of the respective stepping magnets 541, 546, 551 and 556 of the various numerical registers to grounded battery. The numerical registers are thereby restored 25 to their normal positions, whereupon a circuit is completed from ground through the brushes 558, 553, 548 and 543 and their respective normal contacts, terminal 437, brush 415, back contact and armature and 30 winding of stepping magnet 416 to battery and ground. Magnet 416 causes the control switch to take one step to restore such switch to its normal position.

When the control switch reaches its normal position a circuit is closed from grounded battery through the winding of the power magnet of sequence switch 440, lower left-hand contact of sequence switch spring 480, terminal 481, brush 411 and the 40 contact of sequence switch 438 to ground. Sequence switch 440 is thereupon advanced to its normal position.

When the district sequence switch 210 leaves position 10½ the circuit of relay 400 is opened and this relay deenergizes, causing in turn the deenergization of relay 404. When therefore, sequence switch 440 reaches position 1 a circuit is completed for restoring the class register sequence switch 410.

50 This circuit extends from grounded battery, winding of the power magnet of sequence switch 410, upper right-hand contact of sequence switch spring 408, contact of sequence switch spring 482, terminal 481, brush 411, right-hand armature and back contact of relay 404, and the right-hand armature and back contact of relay 400 to ground. This circuit causes the class register switch to be advanced out of position 8 55 and into position 1.

With the district sequence switch 210 in position 15 and the office sequence switch 310 in position 8, a conversational circuit is established through to the trunk 328, 329, 110 and 111, to their normal positions,

60 When the calling subscriber later hangs up

his receiver the circuit of relay 204 is opened. Relay 204 in turn causes the deenergization of relay 205. Relay 205 completes the circuit from ground through its right-hand normal contact, the upper contacts of sequence switch 219, and the winding of the power magnet of the sequence switch 210, to grounded battery, to cause this sequence switch to move from position 15 into position 18.

70 In position 18, a circuit is completed from grounded battery, winding of down-drive magnet 226, right-hand contacts of sequence switch spring 219, to ground at the back contact of relay 205. When the brush shaft 248 reaches its normal position a circuit is completed from grounded battery, winding of the power magnet of sequence switch 210, contact of sequence switch spring 217, normal commutator segment 229, commutator brush 228 to ground at sequence switch spring 223 for moving sequence switch 210 out of position 18 and into position 1.

75 As sequence switch 210 leaves position 16 the holding circuit of relay 300 is interrupted at the right-hand contacts of sequence switch spring 222. Relay 300 releases its armatures and completes a circuit from grounded battery, winding of the power magnet of sequence switch 310, lower right-hand contact of sequence switch spring 303, left-hand armature and back contact of relay 300 to ground, for moving this sequence switch out of position 8 and 80 into position 18.

85 In position 18 of sequence switch 310 a circuit is completed from grounded battery, winding of down-drive magnet 319, lower left-hand and upper right-hand contacts of sequence switch spring 301 to ground. When the brush shaft 326 reaches its normal 90 position a circuit is completed from grounded battery, winding of the power magnet of sequence switch 310, upper right-hand contact of sequence switch spring 303, 95 normal commutator segment 313, commutator brush 312 to ground, for moving this sequence switch out of position 18 and into 100 position 1.

105 At the time relay 205 becomes deenergized it opens at its left-hand armature the circuit which has been holding relays 206 and 104 energized. Relay 104 on deenergizing completes a circuit as follows for restoring the individual line switch to its normal position: grounded battery, winding and armature and back contact of stepping magnet 105, lowermost armature and back contact of relay 104, right-hand armature and back contact of relay 103, brush 107, off-normal segment 112 to ground. The stepping magnet 105 interrupts its own circuit and restores the brushes 106, 107, 108, 109, 110 and 111, to their normal positions, 115 whereupon the brush 107 disengages seg- 120

125 130

ment 112 and opens the operating circuit of the stepping magnet. All of the apparatus has now been restored to its normal condition and is ready for reuse.

5 From the foregoing description it is obvious that the groups of register relays shown in Fig. 5 are operated only during the period immediately preceding and during the duration of the selective operation 10 which they are to control. It is further obvious that each group of relays may be used repeatedly to control selective operations of a plurality of switches. In the embodiment shown relays 613 to 618 control 15 brush selection at the district and office selector switches. Relays 606 to 611 inclusive control the group selecting operations at the various switches and relays 601 to 604 control the setting of the class register switch. It is further obvious that the impulse generating device 623 is preferably 20 common to all the senders of an exchange since its brushes may be multiplied to the various senders in desired combinations and 25 no possible confusion can result.

The usual advantage of the use of a common impulse generating device in connection with a translator switch is thus attained. This advantage lies mainly in the simplicity 30 in which a change of routing may be accomplished. When the translator switch is employed in combination with an impulse generating device it is only necessary to change the connections to the brushes of the impulse 35 generating device, and the changes are immediately effective on all of the senders. An additional set of translator terminals has been shown to further illustrate the method of connecting to the impulser 623.

40 What is claimed is:

1. In a telephone exchange system, a plurality of automatic switches, a primary registering device, a plurality of secondary registering devices, means to position said primary registering device, means to position each of said secondary registering devices a plurality of times in accordance with a single setting of said primary registering device, and means to operate said automatic 45 switches under the control of said secondary registering devices.

2. In a telephone exchange system, a primary registering device, a secondary registering device, means to position said primary registering device, and means to operate said secondary registering device a plurality of times in accordance with a single setting of said primary registering device.

60 3. In a telephone exchange system, automatic switches, a primary registering device, an impulse generator, means to position said primary registering device, a secondary registering device, means to operate said secondary registering device a plural-

ity of times under the control of said impulse generator in accordance with a single setting of said primary registering device, and means to operate said automatic switches under the control of said registering devices. 70

4. In a telephone exchange system, a primary registering device, a group of relays comprising a secondary registering device, means to position said primary registering device, and means to repeatedly operate said relays in variable combinations in accordance with a single setting of said primary registering device. 75

5. In a telephone exchange system, automatic switches, a plurality of primary registering devices, a secondary registering device associated with each of said primary registering devices, an impulse generator common to said primary registering devices, means to position a desired one of said primary registering devices, means to repeatedly operate the associated secondary registering device under the control of said impulse generator in accordance with a single setting of said positioned primary registering device and means to operate said automatic switches under control of said registering devices. 80 85

6. In a telephone exchange system, a primary registering device, a group of relays comprising a secondary registering device, an impulse generator, means to position said primary registering device, and means to repeatedly operate said relays in variable combinations under the control of said impulse generator in accordance with a single setting of said primary registering device. 90 95

7. In a telephone exchange system, a plurality of primary registering devices, a group of relays comprising a secondary registering device associated with each of said primary registering devices, an impulse generator common to said primary registering devices, means to position a desired one of said primary registering devices, and means to repeatedly operate the associated relays in variable combinations under the control of said impulse generator in accordance with a single setting of said positioned primary registering device. 100 105 110

8. In a telephone exchange system, a plurality of automatic switches, a primary registering device, a plurality of secondary registering devices, means to position said primary registering device, an impulse generator, means to repeatedly position each of said secondary registering devices under the control of said impulse generator in accordance with a single setting of said primary registering device, and means to operate said automatic switches under the control of said secondary registering devices. 120

9. In a telephone exchange system, a plurality of automatic switches, a plurality of

- primary registering devices, a plurality of secondary registering devices associated with each of said primary registering devices, an impulse generator common to said primary registering devices, means to position a desired one of said primary registering devices, means to repeatedly position each of the secondary registering devices associated with said positioned primary registers under the control of said impulse generator in accordance with a single setting of said primary registering devices, and means to operate said automatic switches under the control of said secondary registering devices.
15. In a telephone exchange system, a plurality of automatic switches, a primary registering device, a plurality of groups of relays, each of said groups comprising a registering device, means to position said primary registering device, an impulse generator, means to repeatedly operate said groups of relays in variable combinations under the control of said impulse generator in accordance with a single setting of said primary registering device, and means to operate said automatic switches under the control of said secondary registering devices.
20. In a telephone exchange system, a plurality of automatic switches, a primary registering device, a plurality of groups of relays, each of said groups comprising a secondary registering device, means to position said primary registering device, means to repeatedly operate each of said groups of relays in variable combinations in accordance with a single setting of said primary registering device, and means to operate said automatic switches under the control of said 25 relays.
25. In a telephone exchange system, a plurality of automatic switches, a primary registering device, a plurality of groups of relays, each of said groups comprising a secondary registering device, means to position said primary registering device, means to repeatedly operate each of said groups of relays in variable combinations in accordance with a single setting of said primary registering device, and means to operate said automatic switches under the control of said 30 relays.
30. In a telephone exchange system, a plurality of automatic switches, a primary registering device, a plurality of groups of relays, each of said groups comprising a secondary registering device, means to position said primary registering device, means to repeatedly operate each of said groups of relays in variable combinations in accordance with a single setting of said primary registering device, and means to operate said automatic switches under the control of said 35 relays.
35. In a telephone exchange system, a plurality of automatic switches, a primary registering device, a plurality of groups of relays, each of said groups comprising a secondary registering device, means to position said primary registering device, means to repeatedly operate each of said groups of relays in variable combinations in accordance with a single setting of said primary registering device, and means to operate said automatic switches under the control of said 40 relays.
40. In a telephone exchange system, a plurality of automatic switches, a primary registering device, means to position said registering device, means to operate one of said automatic switches in a selective movement in accordance with the set position of said registering device, means to release said registering device as soon as the selective movement controlled by it is completed, and means operative thereafter to reposition said 45 registering device to control another of said automatic switches.
45. In a telephone exchange system, calling and called subscribers' lines, a plurality of automatic switches for interconnecting said lines, a primary registering device, means to position said primary registering device under the control of a calling subscriber, a plurality of secondary registering devices, means to repeatedly position each of said 50 secondary registering devices in accordance with a single setting of said primary registering device, and means to operate said automatic switches under the control of said secondary registering devices.
50. In a telephone exchange system, calling and called subscribers' lines, a plurality of automatic switches for interconnecting said lines, a primary registering device, means to position said primary registering device in response to a plurality of series of impulses transmitted over a calling line, a plurality of secondary registering devices, means to repeatedly position each of said 55 secondary registering devices in accordance with a single setting of said primary registering device, and means to operate said automatic switches under the control of said secondary registering device.
55. In a telephone exchange system, calling and called subscribers' lines, a plurality of automatic switches for interconnecting said lines, a primary registering device, means to position said primary registering device in response to a plurality of series of impulses transmitted over a calling line, a plurality of secondary registering devices, means to repeatedly position each of said 60 secondary registering devices in accordance with a single setting of said primary registering device, and means to operate said automatic switches under the control of said secondary registering devices.
60. In a telephone exchange system, calling and called subscribers' lines, a plurality of automatic switches for interconnecting said lines, a primary registering device, means to position said primary registering device in response to a plurality of series of impulses transmitted over a calling line, a plurality of secondary registering devices, means to repeatedly position each of said 65 secondary registering devices in accordance with a single setting of said primary registering device, and means to operate said automatic switches under the control of said secondary registering devices.
65. In a telephone exchange system, calling and called subscribers' lines, a plurality of automatic switches for interconnecting said lines, a primary registering device, means to position said primary registering device in response to a plurality of series of impulses transmitted over a calling line, a plurality of secondary registering devices, means to repeatedly position each of said 70 secondary registering devices in accordance with a single setting of said primary registering device, and means to operate said automatic switches under the control of said secondary registering device.
70. In a telephone exchange system, calling and called subscribers' lines, a plurality of automatic switches for interconnecting said lines, a primary registering device, means to position said primary registering device in response to a plurality of series of impulses transmitted over a calling line, a plurality of secondary registering devices, means to repeatedly position each of said 75 secondary registering devices in accordance with a single setting of said primary registering device, and means to operate said automatic switches under the control of said secondary registering device.
75. In witness whereof, I hereunto subscribe my name this 9th day of April, A. D. 1921.
80. WALTER P. ALBERT.
